UNITED STATES PATENT OFFICE.

EDMUND S. SAYER, JR., OF OKLAHOMA, OKLAHOMA TERRITORY.

FIELD CHEST AND DESK.

No. 823,700.

Specification of Letters Patent.

Patented June 19, 1906.

Application filed November 20, 1905. Serial No. 288,223.

To all whom it may concern:

Be it known that I, EDMUND S. SAYER, Jr., a citizen of the United States, residing at Oklahoma city, in the county of Oklahoma, 5 Territory of Oklahoma, have invented certain new and useful Improvements in Field Chests and Desks, of which the following is a specification.

The object of my invention is to provide an improved construction of field-chest which may be easily transported from place to place as part of a soldier's equipment or impedimenta in the field, which will be durable in construction and will be able to withstand the rough treatment to which its use will subject it, which will occupy very little space in a tent or the like, and at the same time will provide a convenient form of writing-desk and wherein apparel may be placed, and which is provided with an improved construction of legs, which may readily be folded up and when folded will form a substantial part of the bracing frame or bars of the structure.

25 For a full description of the invention and the merits thereof and also to acquire a knowledge of the details of construction of the means for effecting the result, reference is to be had to the following description and accompanying drawings, in which—

Figure 1 is a front elevation of my invention with the supporting-legs in extended position. Fig. 2 is a side elevation, the legs being folded. Fig. 3 is an end view thereof. 35 Fig. 4 is a detail view of the locking-bar employed. Fig. 5 is a front view with the doors open and one of the legs shown in folded position and the other extended. Fig. 6 is a vertical transverse section, parts being shown 40 in side elevation.

Corresponding and like parts are referred to in the following description and indicated in all the views of the drawings by the same reference characters.

45 My improved field chest or desk comprises a casing, preferably constructed of veneers or other suitable light wood, provided with two sides 1, a top 2, bottom 3, and back 4. These main parts are preferably braced at their 50 edges by wooden strips 5 at the sides and back and top, which are held rigidly together, preferably by metallic corner-pieces 6, as shown, and the edges of the sides between said bracing-strips are preferably covered 55 with metallic sheathing 7 at both top and bottom.

The combined writing desk and chest is divided into any preferred number of compartments, arranged one above the other and separated by partition-walls 8. Each of said compartments is provided at its front with a door 9, and all of said doors are hinged at one edge to open downwardly and outwardly, as shown in the vertical transverse section in the drawings, and each door is limited and guided in its movement by means of metallic strips 10, which are secured to opposite sides of the door and are slotted to receive a stud or screw 10^a. Each door 9 is provided at its free edge with a lock 11, which is designed to engage with coacting keepers 12 on the adjacent portion of the casing when the door is moved into closed position. One of said compartments (designated 13) is intended for use as a writing-desk, and to this end it is provided with any preferred construction of pigeonholes 14. Sundry of the other compartments are intended as storage-receptacles for garments or wearing-apparel or for other articles, and said compartments (designated 15) are provided with extensible drawers 16, each of which comprises a back 16^a and a bottom horizontal member 16^b, which is mounted to slide horizontally into and out of its respective compartment within 85 guides 17, as shown.

The supporting-legs for the chest are so arranged that they may be folded out of the way when it is desired to transport the chest from one place to another, and each of said legs (designated 18) is secured to one member 19 of a leaf or strap hinge, the other member 20 of which is attached by screws or the like to the lower end of one of the side bracing-strips 5. The said hinges are located on the outer sides of both the strips and the legs, and the legs are designed to fold inwardly, as indicated in the drawings. Each leg is attached intermediate of its ends to one end of a metal brace 21, the other end of which is provided with a metal stud 22, working in the horizontally-extending metal-bounded slot 23 of a bottom brace 24, and the said braces and legs are so arranged with respect to their relative lengths that the legs when folded will form a continuation of the lower bracing-strip 24, as indicated in the bottom plan view, and at the same time it will be noted that the strap or leaf hinges comprising the two members 19 and 20 have their pintles 25 at the lower corners of the chest when the legs are folded inwardly, so that

they serve as metallic corner-pieces to preserve the lower corners of the chest from injury.

In order to hold each of the legs in its folded position, I preferably employ a threaded bolt 26, which is designed to extend through or into the bottom 3 of the casing or chest proper, there to engage in a nut 26^b, which is preferably countersunk in the inner face of the said bottom. This threaded bolt 26 has a nut or washer 26^a, which is set in a well in the leg 18 and under the leaf of the hinge 19, which prevents it from being wholly withdrawn from the leg, thus avoiding any loose parts. As shown, the locking-bolt 26 serves the additional function of assisting in attaching the member 19 of the strap-hinge to the leg.

27 designates a locking-bar which is provided at its lower end with an inwardly-extending hook 28, which is designed to catch under the outer one of the lower braces 24 and to extend upwardly over the closed doors 9 in position to prevent access to the respective locks of the doors, and said locking-bar is provided at its upper end with a hasp 29, designed to receive a staple 30, in which a padlock 31 may be located. By this means, in addition to protecting the locks of the various doors from being tampered with, the locking-bar 27 serves as an additional strengthening-brace for the chest, and the chest is provided at top and bottom with handles which are preferably formed of strips of rope 32, knotted at their ends and passed through cleats 33.

From the foregoing description, in connection with the accompanying drawings, it will be seen that I have provided a very durable and strong construction of field-chest and one that will be a great convenience to a soldier in the field, as it may be readily transported from place to place and may hold various articles of apparel without occupying much space in the tent or the like, as well as serving as a convenient form of writing-desk.

Having thus described the invention, what is claimed as new is—

1. A device of the character described comprising a chest or the like provided with strengthening or binding strips at its sides, hinges one leaf of each of which is secured to the lower ends of the respective binding-strips and foldable legs carried by the other leaf of said hinges and arranged to fold inwardly whereby the pintle of the hinge will form a metallic corner-brace when the legs are in folded position.

2. A device of the character described comprising a chest or the like provided with side and bottom strengthening-strips, and legs

pivotedly attached to said chest and designed to fold inwardly at opposite sides of the bottom binding-strip and forming a continuation thereof.

3. A chest or the like provided at its bottom with binding or strengthening strips extending short of the sides thereof, and foldable legs arranged to form a continuation of said bottom binding-strip when in folded position.

4. A device of the character described comprising a chest or the like provided at its edges with strengthening or binding strips metallic corner-pieces for the upper ends of the same, strap-hinges secured to the lower ends of said strips with their pintles projecting, and foldable legs carried by said hinges and arranged to fold inwardly, whereby the pintles of said hinges form bottom corner-pieces.

5. A device of the character described comprising a chest or the like provided with bottom binding or strengthening strips, legs designed to fold inwardly against opposite ends of said strips whereby to form a continuation thereof, and means for locking the said legs in folded position.

6. A device of the character described comprising a chest or the like, leaf or strap hinges having one member attached to the chest at the lower face thereof, and legs attached to the other member of said hinge, a locking-bolt serving as one of the attaching means between the legs and the hinge members, and means designed to engage said bolts to hold the respective legs in folded position.

7. A device of the character described comprising a chest divided into a series of compartments, a door for each of said compartments, said doors being provided with independent locking means, and a locking-bar having means whereby it may be secured to said chest and extend over all of said door-locking means.

8. A device of the character described comprising a chest or the like divided into compartments each of which is provided with a door having independent locking means, and a locking-bar provided at one end with a hook whereby it may be detachably engaged with one end of said chest and arranged to extend over all of the door-locking means, the other end of said locking-bar being provided with means whereby it may be secured to the chest.

In testimony whereof I affix my signature in presence of two witnesses.
